6 Claims. (Cl. 214—8.5)

The present invention relates to a device or tool for subdividing stacks of sheet material for use in conjunction with continually operating sheet feeders for printing presses. The device or tool of the invention is particularly useful for lifting stacks or facilitating the insertion of separation bars as they are customarily inserted in sheet stacks to separate the sheets required for a printing run.

Modern high speed and high output printing presses and other sheet-using machines generally operate with very high sheet stacks. Firms supplying the sheet material also prefer to deliver the same in the form of high stacks. It is obviously more convenient and less expensive to ship and store sheets in the form of comparatively few high stacks, rather than in the form of a greater number of low stacks. Such high stacks must then be lifted in toto or in part from pallets, and the surfaces of the pallets are often quite rough. The weight of high stacks is very great, and the pressure between the individual sheets forming the stacks is correspondingly great. This makes it very difficult to insert the separation bars either at the bottom of a stack or into an intermediate part thereof. Auxiliary devices or tools to facilitate lifting and subdividing of a stack as heretofore known are not satisfactory.

It is a broad object of the invention to provide a novel and improved device or tool which greatly facilitates the lifting of a stack or the insertion of separation bars into a stack, irrespective of the height and the attendant weight of the stack.

A more specific object of the invention is to provide a novel and improved auxiliary tool or device which not only facilitates the lifting or subdivision of a stack of sheets, but also permits lifting or subdivision of a stack without damage to the sheets at or immediately adjacent to the point of insertion of the tool or device, thus avoiding waste of material.

The afore-pointed-out objects, features and advantages of the invention, and other objects, features and advantages which will be pointed out hereinafter, are attained by providing on at least one side of a generally wedge-shaped member one row or several parallel rows of balls or similarly rollable members movable along an endless groove formed in said side of the wedge-shaped member. This groove includes a portion extending substantially lengthwise of the wedge-shaped member, and the balls are guided in this portion so that they protrude from the respective side of the member, whereas they move at or below the level of said side in the remaining part of the groove. Accordingly, the protruding balls constitute in effect a rolling surface between the sheet material and the wedge-shaped member, and such rolling surface will obviously greatly facilitate the insertion of the wedge-shaped member between individual sheets or between the bottom sheet and the surface of the pallet or other supporting surface. The remaining portion of the groove, in which the balls do not protrude from the surface of the wedge-shaped member, serves to return balls continuously to the groove portion in which the balls protrude from the wedge-shaped member.

In the accompanying drawings a preferred embodiment

of the invention is shown by way of illustration, and not by way of limitation.

In the drawing:

FIG. 1 is a cross section of a tool or device according to the invention;

FIG. 2 is a fragmentary longitudinal section of the device or tool;

FIG. 3 is a fragmentary plan view;

FIG. 4 is a plan view of the entire tool or device;

FIG. 5 is a side view of a stack of sheets showing the insertion of two tools or devices according to the invention; and

FIG. 6 is a front view of the stack according to FIG. 5.

Turning first to FIGS. 1 through 4 in detail, the tool or device as exemplified in these figures comprises a generally-wedge-shaped member 1 made of a suitable rigid material, such as metal, wood or plastic. Member 1 should be comparatively light in weight and be convenient to manipulate. In at least one side, but preferably in both sides, of member 1 an endless groove 2 is provided. The groove preferably has the configuration best shown in FIG. 4; that is, it includes two portions 3 and 4 extending substantially lengthwise of member 1 and joined at both ends by curved portions. A plurality of rollable elements, such as balls 8, are placed in the groove—preferably so many that the groove is nearly filled. One of the two lengthwise portions, such as portion 3, is so placed that it is at or near the highest portion of the wedge-shaped member, and the balls in it are so guided that they protrude slightly above the level of member 1. The balls in all other portions of the groove, including portion 4, are so guided that they are at or just below the level of the groove. This can be conveniently affected by making the groove portion 3 shallower than the remainder of the groove, as is clearly shown in FIG. 1.

To facilitate the guidance and retention of the balls in the groove, the latter may be lined with a tubular liner 7, which may be made of metal, such as steel, or a suitable plastic. The portion of the liner extending through groove portion 3 is then cut open to expose balls 8, as is clearly shown in FIG. 1. The liner can also be formed by coating the walls of the groove with a suitable layer of metal or plastic.

Instead of providing only one groove in one side or both sides of member 1, several grooves substantially filled with balls may be provided in each side. A second groove including a closed lengthwise portion 5 and an open lengthwise portion 6 is shown. Furthermore, several aligned sets of grooves and balls may be used, as is shown in FIG. 4.

The tool or device according to the invention is used by simply pushing the same in a conventional manner between the sheets B of a stack S of sheets, two devices being shown in FIGS. 5 and 6, one at the bottom of the stack and the other in an intermediate part of the stack. The stack itself is shown as being placed upon a conventional lifting pallet 9, which does not constitute part of the invention.

As is evident from the foregoing description, the row of protruding balls 8 constitutes a rolling surface or rolling bearing for the sheets or other surface in direct engagement with member 1. As a result, the friction encountered by member 1 when pushed into the stack is greatly reduced.

The balls may be made of plastic or metal, such as steel, and preferably have smooth or polished surfaces.

Extensive tests have shown that the device or tool according to the invention permits a convenient subdividing or lifting even of very high and correspondingly heavy stacks.

While the invention has been described in detail with

respect to a certain now preferred example and embodiment of the invention, it will be understood by those skilled in the art, after understanding the invention, that various changes and modifications may be made without departing from the spirit and scope of the invention, and it is intended, therefore, to cover all such changes and modifications in the appended claims.

What is claimed is:

1. A self-contained manual tool for lifting or subdividing stacks of sheet material, said tool comprising an elongated generally wedge-shaped member having in one of its sides an endless guide track, and a plurality of rollable antifriction elements fitted in said track substantially filling the same and freely movable along the same, said track including a track portion extending substantially lengthwise of said member, said track portion guiding the antifriction elements partly protruding from the general plane of said one side of the member and the remaining portion of the track guiding the antifriction elements below the general plane of said side.

2. A self-contained manual tool for lifting or subdividing stacks of sheet material, said tool comprising an elongated generally wedge-shaped member having in one of its sides an endless guide track, and a plurality of rollable antifriction elements fitted in said track substantially filling the same and freely movable along the same, said track including a track portion shallower than the remaining part of the track, said shallow track portion extending generally lengthwise of said member and guiding the rollable elements in positions partly protruding from the general plane of said one side of the member and the remaining portion of the track guiding the elements below the general plane of said side.

3. A self-contained manual tool for lifting and subdividing stacked sheet material, said tool comprising an elongated generally wedge-shaped member, a tubular endless guide means inserted in one side of said wedge member, said tubular means including a portion extending generally lengthwise of said wedge member and being open in the peripheral outline of said wedge member, and a plurality of rollable elements inserted into said tubular guide means substantially filling the same and movable along the same, said open guide means portion lifting elements therein partly above the peripheral outline of said wedge-shaped member, the remaining portion of said guide means constituting a return path for the elements

passing said open portion of the guide means, said return path guiding the rollable elements within the peripheral outline of said wedge member.

4. A tool according to claim 3, wherein said guide means comprises an endless tube embedded in said wedge-shaped member and being lengthwise slotted along said open portion of the guide means, said open portion being located in substantially the thickest portion of the guide means.

5. A self-contained manual tool for lifting or subdividing stacks of sheet material, said tool comprising an elongated generally wedge-shaped member insertable into a stack at an arbitrarily selected portion thereof, said stack having in at least one of its sides an outer endless guide track and an inner endless guide track encompassed by the outer track, and a plurality of rollable anti-friction elements fitted in said tracks freely rollable along the same, each of said tracks including a track portion extending substantially lengthwise of said member, said lengthwise track portions being mutually parallel and guiding a row of said anti-friction elements partly protruding from the general plane of said one side of the member, the remaining portions of each track guiding the anti-friction elements below the general plane of said one side.

6. A self-contained manual tool according to claim 5, wherein each of said tracks comprises two mutually parallel straight track portions extending substantially lengthwise of said member and curved track portions joining said straight track portions, a row of said rollable elements being guided in one straight track portion of each track above the general plane of said member and in the other below said general plane, one straight track portion of each track guiding the rollable elements above the general plane of the member being disposed closely adjacent to the straight track portion of the other track guiding the rollable elements below said plane.
